DESIGN FOR AN ENSEMBLE DRESS

Emil Schwartz, New York, N. Y.

Application November 11, 1935, Serial No. 59,469

Term of patent 3½ years

To all whom it may concern:

Be it known that I, Emil Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The vertical lines on the front and back of the waist portion of the dress member of the ensemble represent tucks.

The cross hatched lines on the front of the collar portion of the dress member of the ensemble, and on the sleeves and front edge portion of the jacket, represent embroidery.

I claim:

The ornamental design for an ensemble dress, substantially as shown, and described.

EMIL SCHWARTZ.
